Ternstedt Manufacturing Company, Detroit,
Mich., a corporation of Michigan

Application October 5, 1933. Serial No. 49,405

Term of patent 7 years

To all whom it may concern:

Be it known that I, ERIC S. CARLSON, a citizen of the United States, residing at 765 Central Avenue, Detroit, in the county of Wayne and State of Michigan, have invented a new, original, and ornamental Design for an Outside Door Handle or Similar Article for an Automotive Vehicle, of which the following is a specification, reference being made to the accompanying drawing, forming part thereof.

Fig. 1 is a front elevation of an outside door handle or similar article for an automotive vehicle, showing my new design;

Fig. 2 is a plan view of the same;

Fig. 3 is a section along the line 3—3 of Fig. 1.

I claim:

The ornamental design for an outside door handle or similar article for an automotive vehicle substantially as shown.

ERIC S. CARLSON.
